Attorney.*

UNITED STATES PATENT OFFICE.

PHILIP T. SHARPLES, OF ST. DAVIDS, PENNSYLVANIA.

SPINDLE FOR CENTRIFUGAL MACHINES.

1,401,197.

Specification of Letters Patent. Patented Dec. 27, 1921.

Application filed August 6, 1919. Serial No. 315,682.

To all whom it may concern:

Be it known that I, PHILIP T. SHARPLES, a citizen of the United States, residing at St. Davids, in the county of Delaware and 5 State of Pennsylvania, have invented certain Improvements in Spindles for Centrifugal Machines, of which the following is a specification.

This invention is designed primarily to 10 provide improved means for suspending and revolving the bowls of centrifugal machines and particularly to provide, between the spindle and bowl, a flexible coupling of simple character that will permit the revolving 15 bowl to gyrate or follow its natural course without deflecting or straining the spindle, that will permit the use of a comparatively short and stiff spindle with the minimum difficulty in manufacture and use, that will 20 minimize the objectionable effects due to the machine or its parts being out of true or unbalanced, and that will avoid the disadvantages resulting from the use of the familiar long and limber spindle heretofore 25 adopted for the purposes of permitting the gyratory or natural movements of bowls from whatever cause and thus avoiding strain, wear and binding action.

In the accompanying drawings, Figure 1 30 is a broken vertical sectional view of apparatus embodying my invention; Fig. 2 is a sectional view taken on the line 2^x—2^x of Fig. 1, and Fig. 3 is a sectional view taken on the line 3^x—3^x of Fig. 1.

35 In the mechanism shown, by way of illustrating an embodiment of the invention, a spindle 1 is provided with and suspended by the top bearing 2 which is engaged on the pliable bearing 3 held in the cap 4 on the 40 driving wheel or pulley 5, the latter being carried and journaled on the stationary supporting means 6 by the antifriction bearings 7.

A bearing 8, fixed to the bottom of the 45 spindle 1, is provided with a spherical top surface 9 and the depending part 9', and a bowl 10 is provided with a hollow stub-spindle 11 connected with this bearing by the coupling 12 and the pin or studs 13. The 50 coupling 12 is provided with the aperture 14 and the inwardly drawn flange 15, through which the spindle 1 passes freely so as to permit the universal movement of this flange on the surface 9, and with the female thread 55 16 which screws on the male thread 17 of the part 11. The studs 13, fixed in or to the

part 9', are disposed loosely in the diametrically disposed sockets 18, permitting the bowl a limited universal movement relatively to the spindle.

These connections between the spindle and the bowl provide for suspending and revolving the latter positively while permitting it a limited gyratory movement and the capacity to adjust its position automatically 65 in operation.

A bearing 20, supported in the stub-spindle 11 by the spring 21 seated in this spindle, is pressed by the spring against the bottom of the part 9', supplementing the action of 70 gravity in maintaining the desired engagement of the part 15 with the surface 9, as well as acting to restrain the movement of the bowl relatively to the spindle.

In operation, the suspended spindle 1, 75 revolved by the wheel 5, revolves the suspended bowl 10 through the friction between the parts 9 and 15, and the engagement of the studs 13 with the stub-spindle 11. As the flexible coupling provides a universal 80 joint between the parts 1 and 10, each is permitted a limited departure from its correct position with relation to the vertical and the bowl is provided with means supplemental to gravity for restraining the movement of 85 the bowl relatively to the spindle.

Having described my invention, I claim:

1. The combination with a suspended spindle and a bowl, of flexible coupling means 90 for suspending said bowl from and revolving it by said spindle, said means adapted for permitting said bowl a limited universal movement and for restraining said universal movement, and a resilient device adapted to exert pressure in opposite directions on said 95 spindle and bowl longitudinally thereof.

2. The combination of a suspended spindle and a centrifugal bowl, of flexible coupling means for suspending said bowl from and revolving it by said spindle, said coupling means permitting said bowl to move universally and comprising a resilient device acting longitudinally with relation to the axis of revolution for restraining said universal movement.

3. The combination with a suspended spindle and a centrifugal bowl, of flexible coupling means comprising a curved bearing member fixed to one of said parts, a bearing member detachably connected with the other of said parts and engaging said curved bearing member in universally movable re-

lation, and resilient means acting longitudinally with relation to the axis of said bowl to restrain said universal movement.

4. The combination with a suspended spindle provided with a bearing member having a curved surface and a bowl having a stub-spindle, of a coupling member having a universally movable engagement with said curved surface and a detachable engagement with said stub-spindle, and means comprising

ing a device connecting said members whereby said spindle is adapted to revolve said bowl positively and a spring adapted to act in opposite directions on said bearing member and stub-spindle to restrain said universal movement. 15

Signed at West Chester, in the county of Chester and State of Pennsylvania, this 31st day of July, 1919.

P. T. SHARPLES.
